UNITED STATES PATENT OFFICE.

EARL BARNES LEWIS, OF WATERBURY, CONNECTICUT.

VARIABLE CONDENSER.

Application filed June 17, 1925. Serial No. 37,700.

This invention relates to variable condensers for use in radio apparatus, and more particularly to a plate condenser having improved means for reducing the electrical leakage to the minimum.

A further object is to provide a condenser having stationary and movable plates, said stationary plates being mounted in a plurality of posts which are insulated from 10 their supporting frames by means of insulating balls.

A further object is to provide a device of the above nature which will be simple in construction, inexpensive to manufacture, 15 easy to manipulate, compact, ornamental in appearance, and very efficient and durable in use.

With these and other objects in view, there has been illustrated on the accompanying 20 drawings, one form in which the invention may be conveniently embodied in practice.

Fig. 1 represents a top plan view of the condenser, the movable plates being shown in alignment with the stationary plates and 25 in the position of maximum capacity.

Fig. 2 is a front view of the same.

Fig. 3 is a side view of the same.

Fig. 4 is a sectional view of the condenser with the supporting top plate removed, the 30 movable and stationary condenser plates being shown in the position of minimum capacity.

Fig. 5 is a sectional view on an enlarged scale of the end of one of the posts upon 35 which the stationary plates are mounted, and illustrating the insulating ball seated in said post and in an aperture of the adjacent supporting plate.

Referring now to the drawings in which 40 like reference numerals denote corresponding parts throughout the several views, the frame of the condenser is made up of a pair of supporting plates 10 and 11 which are connected together by a plurality of rods 12, 45 13, 14, and 15. Between the supporting plates 10 and 11, the condenser is provided with a plurality of movable plates 16 secured upon a rotor shaft 17, and a plurality of stationary plates 17^a arranged in spaced 50 relation to said movable plates. The shaft 17 is countersunk in its lower end forming a conical seat 18 for a pointed adjustable screw 19, the threads of which engage in a stationary nut 20 mounted in the bottom of 55 the supporting plate 11. The upper bearing for the shaft 17 comprises an annular jour-

nal member 21 which is carried by the upper plate 10.

In order to secure the supporting frame to a radio set or other instrument, the upper supporting plate 10 is provided with three upstanding rods 22, 23, and 23^a. The rods 22, 23, and 23^a are adapted to engage against the panel of the radio set and may be tapped to receive suitable attaching screws passing through said panel. The upper extremity of the rotor shaft 17 is made sufficiently long to extend out through the panel and is adapted to have a suitable tuning dial attached thereto, in any suitable manner, as 70 by a set screw.

Both sets of condenser plates 16 and 17^a are made substantially semi-spherical in shape, and said stationary plates 17^a have projections 24 and 25 at their opposite ends 75 for fitting into a pair of posts 26 and 27. The posts 26 and 27 are provided with countersunk recesses 28 at their opposite ends to provide circular line contacts with the inner sides of two pairs of insulating balls 29, as most clearly shown in Fig. 5. The outer sides of said balls 29 are seated in apertures 30 formed in the upper and lower supporting plates 10 and 11, said apertures also 80 engaging said balls along circular line contacts.

By means of this construction, it will be evident that electrical leakage will be reduced to the minimum, and consequently 85 the loss of signal strength which occurred in radio receiving sets employing the old type of condenser having surface contact insulation will be avoided.

While there has been disclosed in this 90 specification one form in which the invention may be embodied, it is to be understood that this form is shown for the purpose of illustration only, and that the invention is not to be limited to the specific disclosure 95 but may be modified and embodied in various other forms without departing from its spirit. In short, the invention includes all the modifications and embodiments coming within the scope of the following claims.

Having thus fully described the invention, 100 what is claimed as new, and for which it is desired to secure Letters Patent, is:

1. In a variable condenser, a pair of end 105 supporting plates, means to connect said plates to form a rigid frame, a rotor shaft mounted in said supporting plates, a plurality of movable condenser plates secured

- to said shaft, a plurality of stationary condenser plates interposed between and spaced from said movable plates, a pair of posts having hollow ends for supporting said stationary plates, and insulating means extending into the ends of said posts and contacting therewith only upon the lines of the inside edges of said hollow ends for holding said posts between said supporting plates.
- 5 2. In a variable condenser, a pair of end supporting plates, means to connect said plates to form a rigid frame, a rotor shaft mounted in said supporting plates, a plurality of movable condenser plates secured to said
- 10 shaft, a plurality of stationary condenser plates interposed between and spaced from said movable plates, a pair of posts for supporting said stationary plates, and insulating balls between said supporting plates and the ends of said posts for holding said posts in rigid position.
- 15 3. In a variable condenser, a pair of end supporting plates, means to connect said plates to form a rigid frame, a rotor shaft mounted in said supporting plates, a plurality of movable condenser plates secured to said shaft, a plurality of stationary condenser plates interposed between and spaced from said movable plates, a pair of posts for supporting said stationary plates, and insulating balls seated in the ends of said posts and in said supporting plates whereby the electrical leakage will be reduced.
- 20 4. In a variable condenser, a pair of end supporting plates, means to connect said plates to form a rigid frame, a rotor shaft mounted in said supporting plates, a plurality of movable condenser plates secured to said shaft, a plurality of stationary condenser plates interposed between and spaced from said movable plates, a pair of posts for supporting said stationary plates, and insulating balls separating said posts from said supporting plates for minimizing electrical leakage from said stationary plates.
- 25 5. In a variable condenser, a pair of end supporting plates, means to connect said plates to form a rigid frame, a rotor shaft mounted in said supporting plates, a plurality of movable condenser plates secured to said shaft, a plurality of stationary condenser plates interposed between and spaced from said movable plates, a pair of posts for supporting said stationary plates, and insulating balls seated in said apertures and in the ends of said posts, whereby electrical leakage will be reduced.
- 30 6. In a variable condenser, a supporting frame, a rotor shaft mounted in said frame and carrying a plurality of movable condenser plates, and a plurality of stationary condenser plates spaced from and alternating with said movable plates, said stationary plates being supported upon posts, said posts being insulated at each end from said frame by insulating balls, and said balls having line contacts with said frame and said posts, whereby the electrical leakage from said posts will be minimized.
- 35 7. In a variable condenser, a pair of end supporting plates connected together to form a rigid frame, a rotor shaft, said rotor shaft having a countersunk hole in its bottom end, means adjustably mounted in the bottom supporting plate for extending into said hole, means on the upper supporting plate to form another bearing for said shaft, a plurality of stationary plates interposed between said movable plates, posts for supporting said stationary plates, and insulating balls separating said posts from said supporting plates for minimizing electrical leakage from said stationary plates.
- 40 8. In a variable condenser having alternately arranged movable and stationary contact plates, a supporting frame, a post for supporting said stationary plates, said post having a recess in its end, and an insulated ball seated in said recess, said supporting frame having a seat for the outer side of said ball, whereby electrical leakage will be reduced to the minimum.
- 45 In testimony whereof, I have affixed my signature to this specification.
- 50 EARLE BARNES LEWIS.
